US00D636775S

(12) **United States Design Patent**
Kuroda et al.

(10) **Patent No.:** **US D636,775 S**
(b4) **Date of Patent:** **** Apr. 26, 2011**

(54) **SCANNER**

(75) Inventors: **Satoshi Kuroda**, Kahoku (JP); **Hiroyuki Kuroda**, Kahoku (JP); **Minoru Sugitani**, Kahoku (JP); **Toshiki Satoji**, Milan (IT); **Alvise Gangarossa**, Milan (IT)

(73) Assignee: **PFU Limited**, Kahoku-shi (JP)

(**) Term: **14 Years**

(21) Appl. No.: **29/364,502**

(22) Filed: **Jun. 24, 2010**

(30) **Foreign Application Priority Data**

Apr. 7, 2010 (JP) 2010-008731

(51) LOC (9) Cl. **14-02**

(52) U.S. Cl. **D14/422; D14/453**

(58) **Field of Classification Search** D14/420-425, D14/462-470, 389, 125, 399; D18/50, 54, D18/55, 53, 36-39, 14, 18-21, 49, 52, 51, D18/54.4; 358/400, 401, 448, 474, 486-488, 358/496; 382/312, 317, 321, 315; 400/613, 400/613.1-613.4, 690.1-690.4, 691-694, 400/88, 175; 399/107, 379, 380, 211, 212; 235/462.11, 462.41, 472.01, 470, 462.43; 361/680, 681

See application file for complete search history.

(57) **CLAIM**

The ornamental design for a scanner, as shown and described.

DESCRIPTION

FIG. 1 is a front perspective view of a scanner showing our new design;

FIG. 2 is a front view thereof;

FIG. 3 is a top plan view thereof;

FIG. 4 is an enlarged fragmentary front perspective view thereof; and,

FIG. 5 is another enlarged fragmentary front perspective view thereof.

The broken lines in the drawings are for illustrative purposes only and form no part of the claimed design.

1 Claim, 2 Drawing Sheets
